UNITED STATES PATENT OFFICE.

RAYMOND A. UTKE, OF ROCK ISLAND, ILLINOIS.

PHOTOPRINT ROLLER.

Application filed July 24, 1920. Serial No. 298,746.

To all whom it may concern:

Be it known that I, RAYMOND A. UTKE, a citizen of the United States, residing at Rock Island, in the county of Rock Island and

5 State of Illinois, have invented certain new and useful Improvements in Photoprint Rollers, of which the following is a specification.

My invention has reference to photoprint rollers, such as are used for imparting the 10 desired gloss to the prints by what is known as the ferrotype process. In this process the prints are laid face downward on the ferrotype board and subjected to a pressure from above, usually by means of a roller operated 15 by hand. If the pressure exerted on the print is not uniform the print will stick to the board in places, giving a mottled effect to the face thereof. In order to secure the 20 desired effect it is necessary to use considerable force, and even then the results are not always satisfactory.

The purpose of my invention is to secure a greater uniformity of pressure, in applying the same to the prints, resulting in a 25 more perfect finish thereof. This I accomplish by means of a roller, and mounting therefor, to which the force is applied largely at both ends, and which is provided with weight devices to assist in holding the 30 roller closely to its work.

In the drawings:

Fig. 1 is a front elevation of the invention.

Fig. 2 is a plan view thereof.

Fig. 3 is a cross-section on the broken line 35 3—3 of Fig. 2.

1 is a handle, adapted to be grasped by both hands of the operator, provided at its ends with enlargements 2, projected downwardly into bearings 3, in which is journaled 40 the shaft of a roller 4, of usual construction.

The upper faces of the members 2 are provided with depressions 5, fitted to receive the outer parts of the palms of the operator's hands.

In operation, the handle is grasped by the 45 hands of the operator with the hands bearing downwardly upon the end members 2, while the roller is passed backwards and forwards over the prints, until they receive a sufficient amount of gloss. On account of 50 the members 2 conforming to the shape of the hand, the work is less tiresome, and there is less danger of the hands becoming calloused. The enlargements 2 also add weight to the tool, and aid in giving a uniform 55 pressure to the print. This uniformity is also aided by the hand pressure at each end of the tool. In case the pressure of one hand is temporarily less than that of the other hand, the weighted member tends to 60 hold that end of the roller to its work, so that there is a requisite amount of contact of the roller at all times.

It is obvious that changes can be made in the form and adaptation of the invention 65 without departing from the spirit thereof.

What I claim and desire to secure, is:

1. A device of the class described, comprising a handle provided at its ends with weighted members, and a roller operatively 70 connected with said members in parallel relation with said handle.

2. A device of the class described, comprising a handle, provided at its ends with weighted members, having hand-fitting depressions in their upper faces, and a pressure applying device connected with the 75 ends of said handle.

In testimony whereof I affix my signature.

RAYMOND A. UTKE.
